UNITED STATES PATENT OFFICE

WILLIAM H. BAILEY, OF PUEBLO, COLORADO, ASSIGNOR TO THE COLORADO FUEL AND IRON COMPANY, OF DENVER, COLORADO

METHOD OF PRODUCING BEVELED BLADES

Application filed July 15, 1930. Serial No. 468,118.

My invention relates to a method of producing blades. The principal object is to provide a beveled edge on stock produced by rolling.

5 An object of the invention is to produce beveled-edge blades without shearing or forging. Where a high carbon steel is used, as is usual in blades, such material can only be sheared when it is hot. This heating step is 10 eliminated in my process. Where the beveled edge is produced by forging, it is slow and expensive, due to the slow heating and forging processes, which I wish to avoid.

Another object of the invention is to use 15 stock having an even distribution of metal, in order that it may be rolled and not warp or twist out of shape during cooling.

Still another object is to produce scraper and other blades that may be made out of 20 rolled stock by a single operation.

Further objects reside in providing methods of producing from rolled stock blades having beveled ends and irregular beveled edges.

25 A still further object resides in simultaneously making two beveled-edge blades by a single operation.

While the present invention is especially adapted to produce beveled-edge blades for 30 road graders, it is to be understood that this invention is adaptable for making other finished products from rolled stock.

Changes may be made in the embodiments 35 of the invention, hereinafter described, without departing from the spirit and scope of the invention. Like reference characters designate similar parts in the several views.

Figure 1 is a diagrammatic plan view of 40 a machine adapted to produce a beveled edge blade.

Figure 2 is a broken, side elevation of a 45 blade produced on said machine.

Figure 3 is an end elevation looking in the 50 direction of the arrow "A" of Figure 2.

Figure 4 is a diagrammatic, end elevation 55 of another machine for producing a beveled edge blade.

Figure 5 is a broken elevation of stock to 60 be sawed on the machine illustrated in Figure 4.

Figure 6 is an end elevation looking in the direction of the arrow "B" of Figure 5.

Figure 7 is an end elevation of a modification of same.

Figure 8 is a broken side elevation of a 65 blade made from the stock shown in Figures 5, 6 and 7.

Figure 9 is an end elevation taken in the direction of the arrow "C" of Figure 8.

Figures 10 and 11 are diagrammatic plan 70 views of machines adapted for producing blades according to the present invention.

Figures 12 and 13 are broken, side elevations of blades produced on the machines shown in Figures 10 and 11 respectively. 75

Figures 14 and 15 are end elevations looking in the direction of the arrows "D" and "E" of Figures 12 and 13 respectively.

Referring more in detail to the drawing, the reference numeral 16 indicates a frame 70 of a machine adapted for use in the present invention. A motor 17 is mounted on the frame and carries a circular, friction saw 18. The motor is mounted on a movable carriage 19, connected to be advanced by a hand 75 wheel 20.

A rotary chuck is indicated generally by the reference number 21. It is adapted to hold the stock while the saw is advanced toward and through same. 80

Stock 22 is rolled steel with beveled edges 23, best shown in Figure 3. The material 22 is placed in the chuck 21 and the motor carriage is advanced toward the chuck, whereby the saw cuts the material diagonally and 85 bevels the cut at the same time, as shown at 24, to produce a grader blade extension or outboard blade.

The blade shown in Figures 8 and 9 cannot be rolled due to the uneven distribution 90 of metal. Two methods are illustrated for producing such a blade. Figure 4 shows a machine for the purpose. A support 25 is shown for a motor 26. A friction saw 27 is rotated by the motor. A movable carriage 28 carries a chuck indicated generally by the reference character 29. The carriage is operated by a shaft 30 driven by suitable means 95 (not shown).

Symmetrically rolled steel stock 31 curved 100

in opposite directions at either side of a longitudinal axis, such as shown in Figures 5 and 6 is placed in the chuck and the carriage advanced toward the saw. The material is cut at an angle, as shown at 32, to produce two blades 33 and 34. Where desired, the stock may be rolled with beveled edges, as shown at 52 in Figure 7. In this form, the material is sawed at right angles, as shown at 35. Figures 8 and 9 illustrate the finished product irrespective of whether material like that shown in Figure 6 or that in Figure 7 is sawed.

In Figure 10, a table 36 supports a motor 37 and a swivel chuck 38. A steel friction disc 39 is mounted on the motor shaft 40. A handle 41 controls the chuck and a hand wheel 42 is employed to advance the chuck toward the rotating disk 39. This machine produces a beveled end 43, shown in Figure 12.

Figure 11 illustrates a machine adapted to produce an irregular beveled edge. A motor 45 is mounted on a table 44. A sliding chuck 46 comprises a master cam or templet 47 having an irregular edge 48 disposed to follow a guide roller 49. The chuck carries the stock 50 forward with intermittent lateral movements, as the roller 49 engages the recesses and projections on the master cam. A friction disc 51 cuts the edge of the material in conformity with the master cam. Figures 13 and 15 show the finished product of this machine.

Further details of the machines are thought immaterial, since the machines per se form no part of the present invention and may be of conventional design.

In carrying my method into practice, it will be apparent that in several of the forms, the beveled edge of the scraper blade is produced in the presence of heat, induced by friction of the friction saw.

In all of the forms shown, the rolled stock or section is placed in the chuck and either the saw is moved towards the material or vice versa. In either event, there is a constant relation between the movement of the one relative to the other. In the form shown in Figures 4 to 7, two beveled edge scraper blades are made by a single operation. The beveled edges may either be formed by a diagonal cut through the material, as shown in Figure 6, or they may be formed in rolling and the two beveled edged blades severed by a straight cut through the material, as shown in Figure 7.

In the form shown in Figure 10, the swivel chuck is controlled by the handle 41 and advanced towards the saw by means of the hand wheel 42. In the form shown in Figure 11, the sliding chuck follows the contour of the irregular master cam, whereby the material is cut in conformity with the face of the cam. What I claim and desire to secure by Letters Patent is:

1. The method of producing beveled edge blades comprising rolling stock with an even distribution of metal at either side of a longitudinal axis, and then frictionally sawing the stock along the longitudinal axis at an angle, other than a right angle, to a face of the stock, to provide a beveled edge.

2. The method of producing beveled edge blades comprising rolling stock with a curve at either side of a longitudinal axis, and frictionally sawing the stock along said axis at an angle, other than a right angle, to a face of the stock.

3. The method of producing an outboard blade or the like, comprising rolling curved, beveled-edged stock with an even distribution of metal at either side of a longitudinal axis, and then frictionally sawing the stock at an angle to said axis and at other than right angles to the faces of the stock, whereby to produce a diagonal, beveled edge apart from the rolled beveled edges.

4. The method of producing an outboard blade or the like, comprising rolling stock with an even distribution of metal at either side of a longitudinal axis, and then cutting the stock by a single cutting operation at an angle to said axis and at other than right angles to the faces of the stock, whereby to produce a diagonal, beveled edge.

5. The method of producing beveled edge scraper blades and the like, comprising cutting a previously rolled metal strip in a plane oblique to opposite sides of the same, whereby to separate the strip into two parts, at least one of which has a transversely beveled cutting edge, in a single operation.

6. The method of producing beveled edge scraper blades and the like, comprising cutting a previously rolled, curved strip in a plane oblique to the curved surfaces of the strip, whereby to separate the strip into two parts, at least one of which has a transversely beveled cutting edge, in a single operation.

In testimony whereof I hereunto affix my signature.

WILLIAM H. BAILEY.
